UNITED STATES PATENT OFFICE.

JOHN C. COLTRIN, OF LUCAS, KANSAS.

RADIATOR.

1,271,135.

Specification of Letters Patent.

Patented July 2, 1918.

Application filed September 9, 1916. Serial No. 119,257.

To all whom it may concern:

Be it known that I, JOHN C. COLTRIN, a citizen of the United States, residing at Lucas, in the county of Russell and State 5 of Kansas, have invented certain new and useful Improvements in Radiators, of which the following is a specification.

This invention relates to radiators for use in connection with the cooling systems 10 of internal combustion engines, and is adapted particularly for use upon motor vehicles.

The primary object of the invention is to provide a radiator which shall be of simplified and improved construction, and whereby the efficiency of such devices is generally increased.

A further object of the invention is to provide a radiator having the usual water tubes, and wherein the breakage of one or 20 more of the tubes will not affect the operation of the radiator.

A still further object of the invention is to provide a radiator of the character described which is capable of being readily attached to and detached from the vehicle and coupled to the cooling system of the engine thereof, which is provided with tubes, which may be readily removed should 30 it be desired to repair the same and without detaching the radiator in its entirety from the vehicle, which is provided with improved cooling and condensing means, which is adaptable to motor vehicles now in 35 use, and which is simple and inexpensive of construction and maintenance, and which will prove thoroughly efficient in the attainment of the ends for which it is designed.

With these objects in view, together with 40 others which will appear as the description proceeds, the invention resides in the novel formation, combination and arrangement of parts, all as will be described more fully hereinafter, illustrated in the drawings, 45 and particularly pointed out in the claims.

The invention will be best understood by referring to the accompanying drawings, wherein:—

Figure 1 is an elevation of a radiator 50 constructed and arranged in accordance with the invention;

Fig. 2 is a transverse sectional view taken upon line 2—2 of Fig. 1;

Fig. 3 is a similar view taken on line 55 3—3 of Fig. 1;

Fig. 4 is a transverse sectional view taken upon line 4—4 of Fig. 1; and

Fig. 5 is an enlarged sectional view taken through one of the improved radiator tubes.

Referring now more particularly to the 60 drawings, 6 indicates a base tank and 7 a head tank. These tanks are of substantially the same length and width, and are preferably rectangular in cross section, the said tanks being of a length to fit between the 65 frame members of the motor vehicle at the forward end thereof. The base tank has its upper face provided with a plurality of spaced apertures, and a nipple 8 is arranged at the lower portion of the tank and 70 at the rear thereof to be connected with the cooling system of the motor vehicle engine. A drain cock 9 is also connected to the tank at the base thereof so that the contents of the radiator may be drawn therefrom when 75 desired.

Associated with a device of this character is a cap piece 11, the latter being adapted to rest upon and to communicate with the interior of the upper or head piece 7 of the 80 radiator. The upper edges of the side and end portions of the head tank 7 are turned inwardly to provide flanges 12, upon which similarly formed flanges 13 at the lower edges of the cap piece 11 rest. The front 85 and rear or longitudinal walls of the head tank 7 are connected by tubes or air ducts 14, the same being arranged throughout the length of the said head tank to permit of air passing freely through the same. The 90 lower face of the tank 7 is provided with a plurality of apertures arranged in spaced relation and being disposed directly above the apertures in the upper face of the base tank 6.

The front and rear walls of the cap piece 95 11 are connected by tubular members or air ducts 15, the same being arranged in spaced relation throughout the extent of the cap piece and permit of air flowing freely 100 through to the rear portion of the said cap piece. Arranged within the cap piece and disposed horizontally therein, above the tubes 15 is a perforated diaphragm 16, the latter serving to evenly distribute the water 105 within the cap piece over the condensing or air tubes 15. The upper portion of the cap piece is provided with a neck 17, through which water may be poured to the interior of the radiator. A rearwardly extending 110

nipple 18 is arranged upon the cap piece, and by means of which the portion of the radiator is connected to the cooling system of the combustion engine. The cap piece 5 may be of any shape or size, so as to conform to the various types of motor vehicles with which the improved radiator is used. The base and head tanks 6 and 7 are provided at their upper and lower edges and 10 at the ends thereof with outwardly projecting ears 19, the same being perforated, and being adapted to receive tie rods 20, the latter being of a length to connect the head and base tank and to maintain the same in spaced relation. The tie rods are provided inwardly from their upper and lower ends with enlarged portions 21, certain of the said enlargements forming shoulders for the support of the head tank, while the others 15 rest upon the uppermost of the outwardly projecting ears 19 of the base tank to hold the latter properly spaced from the head tank. The extremities of the tie rods are threaded as shown, and binding nuts 22 may 20 be arranged upon the said extremities to firmly bind the said tanks upon the rods. The lower portion of the cap piece 11 is also provided with laterally projecting lugs 23 to rest upon and overlie the uppermost of 25 30 the ears 19 upon the head tank 7 and to receive the upper ends of the tie rods 20.

Brackets 24 are provided for the purpose of securing the improved radiator to the frame of a motor vehicle and the said 35 brackets have upright portions provided with outwardly extending perforated ears 25 through which the lower ends of the tie rods extend, and the foot portions 26 of the brackets rest upon and are bolted as at 40 45 27 to the longitudinal frame members of the motor vehicle. The ears 25 upon the brackets are spaced apart preferably a distance to enable themselves to fit snugly between the spaced ears 19 upon the base tank 6.

From this construction, it will be seen that the device may be readily assembled upon a motor vehicle by extending the lower portions of the tie rods 20 through the 50 alined apertured ears 19 and 25 upon the base tank 6 and brackets 24, and by engaging the ears of the head tank and those of the cap piece with the upper portions of the tie rods. Tightening of the nuts 22 upon 55 the tie rods will firmly bind the base tank 6 upon the brackets 24, and the head tank and cap piece upon the upper portions of the rods. The shouldered portions 21 of the tie rods maintain the upper and lower portions of the radiator in proper spaced relation. 60 65

A plurality of tubes 30 establish communication between the base and head tanks 6 and 7. These tubes may be formed of 65 relatively small metallic pipes, and are

adapted to extend at their extremities with in the registering apertures in the upper and lower faces of the base and head tanks respectively. Each tube is provided adjacent its lower end with a shoulder portion 70 31, under which the gasket 32 is adapted to be positioned so that when the tubes 30 are forced downwardly upon the tank 6, the gaskets will make a water tight connection between the said tubes and tank. The exterior 75 of the opposite end of each of the tubes 30 is threaded as shown, for the reception of a nut 33 and lock washer 34, and a gasket 35 is positioned between each of the washers and the end face of the tank 7 to prevent 80 leakage at the joints between the tubes and the tank. From this construction, it is apparent that upon properly inserting the tubes in the alined apertures in the tanks 6 and 7, and screwing the nuts 33 upwardly 85 so as to bind the lock washers and gaskets against the bottom of the tank 7, a water tight connection will be formed between the tubes and the tanks 6 and 7. It is also obvious that any of the tubes may be removed 90 when required for repair or renewal without disturbing any of the remaining tubes or detaching the radiator from the vehicle. Should any of the tubes become broken or 95 leaky, the same may be detached and the 95 openings in the base and head tanks soldered or in any other manner closed.

Arranged within each of the tubes 30 and preferably at the upper portion thereof is a reducing member 36. These reducing 100 members restrict the openings in the tubes so that water passing downwardly therethrough will drip or flow in a fine stream, whereby the same may be readily cooled. The reducing member also reinforces or 105 strengthens the tube at its clamping end.

The vertically disposed tubes 30 are arranged between the base and head tanks in relatively close relation so that cooling fluid may have free access to the lower tank, and as the vehicle advances, air will contact the said tubes and cool the water within the same. By providing the air ducts or tubes 110 115 14 and 15 in the tanks 7 and 11, the water contained therein will be cooled more or less before entering the vertical tubes 30.

From the foregoing disclosure, it is apparent that I have provided an extremely simple, inexpensive and yet thoroughly efficient radiator for use in connection with 120 combustion engines for cooling the liquid in the cooling systems thereof. The device may be readily attached and detached from the vehicle when required, and yet repairs of the various parts may be easily made without detaching the entire cooling device. 125

While the above is a description of the preferred embodiment of the invention, it is obvious that various changes in the minor details of construction and arrangement of 130

parts may be resorted to, without departing from the spirit of the invention or exceeding the scope of the claims.

What is claimed is:—

- 5 1. In a device of the class described, a pair of superimposed tanks, the said tanks being provided with vertically alined openings, tubes extending loosely at their ends into said openings to establish communication between said tanks, a shoulder projecting outwardly from each of said tubes at the lower end thereof, threads upon the upper ends of said tubes, nuts upon said threads, and gaskets between said shoulder 10 and the lower tank and between said nuts and upper tank.
2. In a device of the class described, upper and lower tanks, pipes establishing communication between said tanks, the upper tank 20 having its upper end open, an inwardly projecting flange defining the open end of said tank, a cap piece having its lower end open, an inwardly projecting flange defining said open end and being adapted to rest upon the flange of said upper tank, outwardly projecting apertured ears on said tanks and

cap piece and the said ears having their apertures alined, rods extending through said apertures, and shoulders on said rods engaged with said ears for maintaining said tanks in spaced relation.

3. In a device of the class described, upper and lower tanks, pipes establishing communication between said tanks, outwardly projecting ears at the upper and lower ends 35 of said tanks, rods extending through said ears, shoulders adjacent the upper and lower ends of said rods engaged with said ears to maintain the said tanks in spaced relation, a cap piece resting on said upper tank, ears projecting outwardly from said cap piece and resting upon the ears at the upper end of said upper tank, the said rods extending through said cap ears, and nuts 40 on the ends of said rods.

In testimony whereof I affix my signature in presence of two witnesses.

JOHN C. COLTRIN.
